Inventor:
Victor H. Greisser,
by Alvin, Davis
His Attorney.

UNITED STATES PATENT OFFICE.

VICTOR H. GREISSE, OF SPOKANE, WASHINGTON, ASSIGNOR TO GENERAL ELECTRIC COMPANY, A CORPORATION OF NEW YORK.

DYNAMO-ELECTRIC MACHINE.

Application filed October 21, 1921. Serial No. 509,324.

To all whom it may concern:

Be it known that I, VICTOR H. GREISSE, a citizen of the United States, residing at Spokane, in the county of Spokane, State of Washington, have invented certain new and useful Improvements in Dynamo-Electric Machines, of which the following is a specification.

My invention relates to dynamo electric machines and has for its object an efficient arrangement for ventilating such machines.

As is well known, the relatively rotating members of dynamo electric machines are provided with radially extending ventilating spaces or ducts through which air is forced for cooling the members of the machine. The entrance or inlet to such ducts, as heretofore constructed, is at right angles to the flow of air in the air gap between the relatively rotating members, thus producing eddies and reverse flow of air in the air ducts, which materially reduces the amount of air entering the ventilating spaces, the effect of these eddies and reverse flow of air being considerably increased with the increase of speed of rotation of the revolving member. In accordance with my invention, in order to secure the maximum flow of air into the ventilating spaces at right angles to the flow of air in the air gap, I provide a gradual change of shape of the entrance or inlet to the ventilating space by a new and novel shaping of the slot closing wedges.

For a better understanding of my invention, reference may be had to the following description taken in connection with the accompanying drawing, in which Fig. 1 is a sectional view of a portion of a dynamo electric machine embodying my invention; Fig. 2 is an enlarged view of a portion of Fig. 1; and Fig. 3 is a view similar to Fig. 2 showing a modification of my invention.

In the drawing, I have shown my invention embodied in an alternating current dynamo electric machine having a stationary member 1 and a rotatable member 2. The stationary member is provided with usual slots 3 which contain windings 4. The member 1 is provided with ventilating spaces or ducts 5 through which cooling air is forced for ventilating the core and windings of the stationary member. The slots 3 have wedges 6 in the top thereof, which act as coil retaining devices. In accordance with my invention,

each of these wedges has its external 55 surface 7 in the ventilating space extending substantially across the width of the slot and angularly disposed with reference to the periphery 8 of the stationary member, whereby the wedges have a substantially triangular 60 cross section in the ventilating space. The inclination of the surface 7 is such that the narrow part of the triangle extends in the direction of rotation of the rotatable member, that is, the trailing tip 9 of the wedge 65 is cut away in the ventilating space. The surface 7 extends substantially across the width of the slot. The movement of the air in the air gap due to the rotation of the rotatable member 2 is at right angles to the ventilating spaces 5, but by shaping the wedges as described above, the shape of the inlet to the ventilating spaces is gradually changed and the air in entering therein will not have to make a right angle turn, thus reducing 75 eddies and improving the circulation of air through the ventilating spaces.

In order not to obstruct the entrance of air into the ventilating space, I also prefer to cut away the wedge at the leading tip so 80 as to have a surface 10 in the ventilating space extending substantially in line with the side of the slot.

The stationary member 1 is of the usual laminated construction with space blocks 11 85 for forming the ventilating spaces 5. In large machines, a number of ventilating spaces are provided in the core structure. The rotatable member 2 is shown as having definite poles 12, but it is understood that 90 my invention is applicable to machines in which both members have distributed windings like stationary member 1.

In the construction shown in Fig. 3, the wedge has a curved surface 7' cut away at 95 the trailing tip 9' instead of being a flat surface as shown on Figs. 1 and 2. By thus shaping the surface 7', a more gradual change of shape of the inlet to the ventilating duct is obtained. In Fig. 3 also, the space 100 blocks 11' have their tips 13 curved away from the direction of rotation of the rotatable member and thereby still further improve the circulation of air through the ventilating spaces.

In the machine as heretofore constructed, air from the air gap is circulated properly through one part of the ventilating duct, but

has been sucked out of another part of the ventilating duct, thereby causing eddies and a reverse flow of air in the latter part of the ventilating duct. The part of the duct out 5 of which air is sucked is located between a slot and a space block, and is that part of the duct first to be passed by a pole. The part of the duct through which air circulates properly is located between a space block 10 and a slot, and is that part of a ventilating duct which is last to be passed by a pole. I have found by actual tests on certain dynamo electric machines, that the application of my invention thereto so smoothed out the 15 flow of air, that 30 to 50 per cent more air flowed through the ventilating ducts than through the same machine without my invention, and that my invention substantially eliminated the whirls or eddies, pockets, and 20 reverse flow of air usually encountered in machines as heretofore constructed.

I desire it to be understood that my invention is not limited to the particular construction shown and described, and I aim in the 25 appended claims to cover all modifications which do not depart from the spirit and scope of my invention.

What I claim as new and desire to secure by Letters Patent of the United States, is:

30 1. In a dynamo electric machine, two relatively movable members, one of said members being provided with slots and a ventilating space, a wedge in the top of each of a plurality of said slots, each of said wedges 35 having its external surface in the ventilating space angularly disposed with reference to the periphery of the member having said slots, said surface extending substantially across the width of the slot, whereby the circulation through said ventilating space is improved.

2. In a dynamo electric machine, two relatively movable members, one of said members being provided with slots and a ventilating space, a wedge in the top of each of a plurality of said slots, each of said wedges having its external surface in the ventilating space angularly disposed with reference to the periphery of the member having 45 50 said slots, whereby said wedge has a substantially triangular cross section in said ventilating space, the narrow part of the triangle extending in the direction of the relative movement of said members, whereby 55 by the circulation through said ventilating space is improved.

3. In a dynamo electric machine, two relatively movable members, one of said members being provided with slots and a ventilating space, a wedge in the top of each of a plurality of said slots, each of said wedges having a surface in the ventilating space extending substantially in line with the side of the slot and its external surface in the 60 65 ventilating space angularly disposed with

reference to the periphery of the member having said slots, said latter surface extending substantially across the width of the slot, whereby said wedge has a substantially triangular cross section in said ventilating 70 space and the circulation through said ventilating space is improved.

4. In a dynamo electric machine, two relatively movable members, one of said members being provided with slots and a ventilating space, a wedge in the top of each of a plurality of said slots, each of said wedges having a surface in the ventilating space extending substantially in line with the side of the slot and its external surface in said ventilating space angularly disposed with reference to the periphery of the member having said slots, whereby said wedge has a substantially triangular cross section in said ventilating space, the narrow part of the 80 85 triangle extending in the direction of the relative movement of said members, whereby the circulation through said ventilating space is improved.

5. In a dynamo electric machine, a rotatable member, a stationary member provided with slots and a ventilating space, a wedge in the top of each of a plurality of said slots, each of said wedges having its external surface in the ventilating space angularly disposed with reference to the periphery of the stationary member, said surface extending substantially across the width of the slot, whereby the circulation through said 90 95 100 ventilating space is improved.

6. A dynamo electric machine, a stationary member, a rotatable member provided with slots and a ventilating space, a wedge in the top of each of a plurality of said slots, each of said wedges having its external surface in the ventilating space angularly disposed with reference to the periphery of said stationary member, whereby said wedge has a substantially triangular cross section in said ventilating space, the narrow part of the 105 110 triangle extending in the direction of rotation of said rotatable member, whereby the circulation through said ventilating space is improved.

7. In a dynamo electric machine, a rotatable member, a stationary member provided with slots and a ventilating space, a wedge in the top of each of a plurality of said slots, each of said wedges having a surface in the ventilating space extending substantially in 115 120 125 line with the side of the slot and its external surface in the ventilating space angularly disposed with reference to the periphery of said stationary member, said surface extending substantially across the width of the slot, whereby said wedge has a substantially triangular cross section in said ventilating space and the circulation through the ventilating space is improved.

8. In a dynamo electric machine, a rota-

- table member, a stationary member provided with slots and a ventilating space, a wedge in the top of each of a plurality of said slots, each of said wedges having a surface in the 5 ventilating space extending substantially in line with the side of the slot and its external surface in the ventilating space angularly disposed with reference to the periphery of said stationary member, whereby said 10 wedge has a substantially triangular cross section in said ventilating space, the narrow part of the triangle extending in the direction of rotation of the rotatable member, whereby the circulation through the ventilating space is improved.
- 15 9. In a dynamo electric machine, a rotatable member, a stationary member provided with slots and a ventilating space, space blocks in said ventilating space having their tips curved away from the direction of rotation of said rotatable member, a wedge in the top of each of a plurality of said slots, each of said wedges having its external surface in the ventilating space angularly disposed with reference to the periphery of the 20 stationary member, said surface extending substantially across the width of the slot, whereby the circulation through the ventilating space is improved.
- 25 10. In a dynamo electric machine, a rotatable member, a stationary member provided with slots and a ventilating space, space blocks in said ventilating space having their tips curved away from the direction of rotation of said rotatable member, a wedge in the top of each of a plurality of said slots, each of said wedges having its external surface in the ventilating space angularly disposed with reference to the periphery of 30 the stationary member, whereby said wedge has a substantially triangular cross section in said ventilating space, the narrow part of the triangle extending in the direction of rotation of said rotatable member, whereby the circulation through the ventilating space is improved.
- 35 11. In a dynamo electric machine, a rotatable member, a stationary member provided with slots and a ventilating space, space blocks in said ventilating space having their tips curved away from the direction of rotation of said rotatable member, a wedge in the top of each of a plurality of said slots, each of said wedges having its external surface in the ventilating space angularly disposed with reference to the periphery of 40 the stationary member, whereby said wedge has a substantially triangular cross section in said ventilating space, the narrow part of the triangle extending in the direction of rotation of said rotatable member, whereby the circulation through the ventilating space is improved.
- 45 12. In a dynamo electric machine, a rotatable member, a stationary member provided with slots and a ventilating space, space blocks in said ventilating space having their tips curved away from the direction of rotation of said rotatable member, a wedge in the top of each of a plurality of said slots, each of said wedges having a surface in the 50 ventilating space extending substantially in line with the side of the slot and its external surface in the ventilating space angularly disposed with reference to the periphery of said stationary member, whereby said wedge has a substantially triangular cross section in said ventilating space, the narrow part of the triangle extending in the direction of rotation of the rotatable member, whereby the circulation through the ventilating space is improved.
- 55 13. In a dynamo electric machine, two relatively movable members, one of said members being provided with slots and a ventilating space, a wedge in the top of each of a plurality of said slots, each of said wedges being cut away at the trailing tip 60 to reduce eddies and improve the circulation through said ventilating space.
- 60 14. In a dynamo electric machine, two relatively movable members, one of said members being provided with slots and a ventilating space, a wedge in the top of each of a plurality of said slots, each of said wedges being cut away at the leading tip so as to have a surface extending substantially in line with the side of the slot, and being cut 65 away at the trailing tip so as to reduce eddies and improve the circulation through said ventilating space.
- 65 15. In a dynamo electric machine, a rotatable member, a stationary member provided with slots and a ventilating space, a wedge in the top of each of a plurality of said slots, each of said wedges being cut away at the trailing tip to reduce eddies and to improve 70 the circulation through said ventilating space.
- 70 16. In a dynamo electric machine, a rotatable member, a stationary member provided with slots and a ventilating space, a wedge in the top of each of a plurality of said slots, each of said wedges being cut away at the leading tip so as to have a surface in the ventilating space extending substantially in line with the side of the slot, and cut 75 away at the trailing tip so as to reduce eddies and improve the circulation of air through said ventilating space.
- 75 17. In witness whereof, I have hereunto set my hand this Oct. 14, 1921.

VICTOR H. GREISSE.
